UNITED STATES PATENT OFFICE

HERMAN A. REBB, OF SOUTHFIELD TOWNSHIP, OAKLAND COUNTY, MICHIGAN, AS-
SIGNOR TO ALL METAL PRODUCTS COMPANY, OF WYANDOTTE, MICHIGAN, A COR-
PORATION OF DELAWARE

TOY FILLING STATION

Application filed July 24, 1931. Serial No. 552,874.

My invention relates to a new and useful improvement in a toy filling station and has for its object the provision of a toy constructed and arranged to simulate a liquid dispensing pump of a general type commonly used at gasoline filling stations.

It is an object of the present invention to provide a toy of this class which will be simple in structure, economical to manufacture, durable, and highly efficient in use.

Another object of the invention is the provision of a device of this class having a compressible liquid container and a receptacle connected therewith so that upon a compressing of the container, the liquid may be forced into the receptacle.

Another object of the invention is the provision of a movable mechanism for compressing the container for forcing the liquid therefrom into the receptacle.

Other objects will appear hereinafter.

The invention consists in the combination and arrangement of parts hereinafter described and claimed.

The invention will be best understood by a reference to the accompanying drawings, which form a part of this specification, and in which,

Fig. 1 is a central vertical sectional view of the invention.

Fig. 2 is a fragmentary sectional view taken on line 2—2 of Fig. 1.

Fig. 3 is a view taken on line 3—3 of Fig. 1.

Fig. 4 is a view taken on line 4—4 of Fig. 1.

The invention comprises a hollow standard 7 having a head 8 on the upper end provided with a peripheral upwardly projecting flange 9 so that a shoulder or resting surface 10 is formed on the head. Positioned on this shoulder or resting surface 10 is a receptacle base 11 projecting upwardly centrally from which is the stud 12 which projects through the centrally positioned inverted cup-shaped portion 13 of the cover 14. This cover 14 engages the upper edge of the transparent cylindrical member 15, the lower edge of which engages a gasket 16 which it serves to press against the receptacle base 11. A nut 17 is threaded on the upper end of the stud 12 and presses the washer 18 which is positioned in embrac-

ing relation on the stud 12 against the upper surface of the inverted cup shaped portion 13. A radially extending groove 19 is formed in the upper face of this portion 13 and the opening 20 through which the stud 12 projects is sufficiently large to permit play so that the opening 20 and the groove 19 will serve as an air relief or vent. Thus the base 11 and the transparent cylinder 15 together with the cover 14 serve as a receptacle for liquid which may be forced from the collapsible liquid container 22 which is suspended from the nipple 21. It is preferred to form the liquid container 22 from rubber so that when the collapsing pressure is released, the container 22 will resume its distended form.

In order to collapse the container 22, I have provided a plate 23 which is swingably mounted on the pin 24 and depends therefrom. A screw 25 is threaded through the standard 7 and provided with a handle 26 whereby this screw may be rotated. Upon threading the screw inwardly, the plate 23 is forced into pressing engagement with the container 22 so as to compress or collapse the chamber thus forcing liquid which may be within the container 22 into the receptacle where it will be visible. Inasmuch as the collapsing of the container 22 is gradual, with the rotation of the screw 25, the filling of the receptacle with the liquid will be gradual, thus simulating the flow of liquid into the transparent container through the operation of a pump handle commonly used in a filling station dispensing pump. To further simulate in appearance such a pump, I provide a hose or flexible tube 27 which is secured at one end to the head 8 and which is provided at its opposite end with the nozzle 28 which may be hung on the hook 29 and detached therefrom at will.

With a construction of this nature, it is believed obvious that the device may be easily and quickly assembled and that it may be economically manufactured and that there are no parts of a complicated construction so that disarrangement of the various parts while in use is rendered quite unlikely.

While I have illustrated and described the preferred form of construction of my inven-

tion, I do not wish to limit myself to the precise details of structure shown, but desire to avail myself of such variations and modifications as may come within the scope of the 5 appended claims.

Having thus described my invention, what I claim as new and desire to secure by Letters Patent is:

1. A toy of the class described, comprising: 10 a hollow standard; a transparent liquid receptacle mounted on said standard; a collapsible liquid container mounted in said standard and communicating with said receptacle; and means operable for collapsing said container and forcing the liquid therein 15 into said receptacle at will.
2. A toy of the class described, comprising: a hollow standard; a transparent liquid receptacle mounted on said standard; a collapsible liquid container mounted in said standard and communicating with said receptacle; and swingable means for collapsing 20 said container and forcing the liquid therein into said receptacle at will.
3. A toy of the class described, comprising: a standard; a transparent liquid receptacle mounted on said standard; a collapsible liquid container communicating with said receptacle; and movable means for collapsing 25 said container and forcing the liquid therefrom into said receptacle at will.
4. A toy of the class described, comprising: a hollow standard; a transparent liquid receptacle mounted on said standard; a collapsible liquid container mounted in said standard and communicating with said receptacle; a swingable member engageable 30 with said container; and rotatable means for moving said swingable member to compress 35 said container and force the liquid therefrom into said receptacle.

In testimony whereof I have signed the foregoing specification.

HERMAN A. REBB.
